JUAN ANTONIO OTERO, OF LA PLATA, ARGENTINA

LUMINOUS TUBE

Application filed June 20, 1929, Serial No. 372,390, and in Argentina August 20, 1928.

This invention relates to glass tubes, either clear, opaque, colored or otherwise, having in their interior a tungsten or other metallic filament conveniently extended therethrough and held in place in the centre of the tube in which a vacuum is afterwards produced or an inert gas is introduced under a low pressure.

The principal difficulty up to the present has consisted in maintaining the metallic filament extended in the centre of the tube and properly insulated so as not to touch the inner walls of the same.

According to the present invention this difficulty is overcome in the manner herein-after described with reference to the accompanying drawings, in which Fig. 1 is a plan view of a strip of mica with a metallic filament threaded therethrough; Fig. 2 is a cross section of the same; Fig. 3 is a sectional view of a tube with the said mica strip and metallic filament inserted therein; Fig. 4 is a representation of a fragment of seven divisions, (say of one meter each) of a tube of ten meters in length, showing the connections from the tungsten filament, through the glass tube, to the main conductors or leads H; Fig. 5 is a letter "M" formed of a tube four divisions (or meters) in length; and Figs. 6, 7, 8 and 9 are modified forms.

Referring to the said drawings, A is a mica strip with a series of open spaces of uniform size, and which, as shown, has the aspect of a ladder to support the filament.

In the centre of each round of the ladder there is a small perforation through which to pass the metallic filament. The width of the mica strip will vary according to the size of the tube to be used, and this size must be sufficient to facilitate its being passed through the tube with the least possible play after being placed in its proper location. The filament may also be held in place by means of hollow glass beads, either cylindrical or spherical, or by mica rings, through which the filament is threaded.

At the ends of the metallic filaments pieces of platinum or copper wire are provided which can be imbedded in the glass for the exterior connections.

The tubes provided with the strip or rings of mica may be curved with the strip, rings, etc., and the filament inside, while those having glass beads may be bent first and the filament with the beads introduced afterwards. 55

Using tungsten wire five one-hundredths of a millimetre in diameter, the tubes may be constructed, say of one meter in length, to be adapted to 220 volts direct or alternating current ("D", Fig. 3), although single filament tubes may be made of any length. The intensity of the light being in proportion to the diameter of the filament utilized, with a filament of greater diameter a stronger light will, of course, be produced, and it is obvious 65 that the points of connection to the exterior may be further between on account of the lesser resistance of the thicker filament.

The letter F, (Fig. 3) shows a tube, being a fragment of a tube of ten metres in length, 70 with its filament running through its entire length, and in it there may be seen at each meter a connecting wire of boracic copper extending outwardly through the tube. These connections to the exterior may be 75 eleven in number, for example, the even numbers being connected to one lead of the supply line, and the odd ones to the other, so that between each two adjacent connection points the 220 volts of the leads pass, 80 and thus on through the succeeding connections they are connected in "quantity" or parallel to the lighting circuit.

These tubes, before the formation of the vacuum therein, may be bent in the lamps or 85 given the form of letters for luminous signs and the like, after which the vacuum is produced.

Figs. 6, 7, 8 and 9 represent sections of 90 tubes in which there may be seen the form in which the metallic filament is supported; Figure 6 being a tube G in which the filament B is held by the mica strip A; Fig. 7 a similar representation of a tube in which 95 the filament is supported by glass beads J; Fig. 8 being another section of tube G in which the filament is supported by mica rings or disks L, which in their turn are held by the hollow glass beads J; and Fig. 9 is a 100

section of a glass tube G in which the filament B is held in place by mica rings K.

Fig. 5 is a representation of a large letter "M" formed of a tube of the class described.

8 The outlets designated by the numbers 1, 3 and 5 are connected to one line of the circuit and the outlets 2 and 4 to the other.

10 The attractive and fancy luminous letters and designs made with these tubes have the advantage of economy, facility of formation and freedom from danger.

15 The tubes of this kind may be operated on the ordinary 220 or 110 volt distribution circuits, since by merely varying the distance between the contact points they may be adapted to any available voltage, thus doing away with the necessity for transformers for producing the high tension current which is indispensable in the use of luminous tubes of 20 the usual types using rarefied gases.

25 It is understood that the forms of the invention described and illustrated are merely illustrative, and that changes of the details of construction which naturally occur to those skilled in the art, will not depart from the spirit of the invention, as set forth in the appended claims.

Having described my invention, what I claim and desire to protect by Letters Patent of the United States of America, is:

30 1. A lamp tube having a filament support consisting of a mica tape having holes therein, a metallic filament threaded therein and spaced from the walls of said tube.

35 2. A lamp tube having a filament support consisting of mica rings having holes therein, a metallic filament threaded therein and spaced from the walls of said tube.

Signed at Buenos Aires, Argentine Republic, May 24, A. D. 1929.
40 JUAN ANTONIO OTERO.
